H. B. CLEGG

VANITY CASE

Filed May 29, 1925

Inventor

Harry B. Clegg

By Joseph A. Miller

Attorney

UNITED STATES PATENT OFFICE.

HARRY BLISS CLEGG, OF ATTLEBORO, MASSACHUSETTS.

VANITY CASE.

Application filed May 29, 1925. Serial No. 33,674.

To all whom it may concern:

Be it known that I, HARRY BLISS CLEGG, a citizen of the United States, residing at Attleboro, in the county of Bristol and State of Massachusetts, have invented new and useful Improvements in Vanity Cases, of which the following is a specification.

This invention relates to certain new and useful improvements in vanity cases and 10 pertains more particularly to a powder dispenser which is carried by a side of the case.

The primary object of the invention is to provide a dispenser of simple and economical construction, which is removably connected to a side of the case, whereby upon removal to permit same to be easily refilled.

In the drawings:—

Figure 1 is a plan view of the invention, in full open position;

20 Figure 2 is a section on line 2—2 of Fig. 1 and

Figure 3 is a view similar to Fig. 2, of a modified form of the invention.

In proceeding in accordance with the 25 present invention, the dispenser is composed of a body formed with a generally circular top 1 of concavo-convex cross-section having a central opening 2, the latter preferably of circular form. The top 1 has an outwardly extending flange 3 which is secured to and within the upper side of a ring 4, the latter side being offset to form a seat 5 on which seat the top 1 is supported. A removable closure 6 has a rim 7 which frictionally engages over the lower side of the ring 4. The bottom of the closure 6 is formed with a circular upwardly extending bead 7' to form a support for the marginal or peripheral portion of a piston-like or expeller member 8. The member 8 is formed of thin spring metal and is of concavo-convex cross-section with its convex side facing the opening 2.

The ring 4 is formed to be received in a 45 side S of a vanity case and is frictionally held therein, being cut away at 9 and 10 to provide space for the hinge H and catch C of the vanity case, which space also affords a means of enabling a sharp instrument to be introduced to pry out the device from the side of the vanity case.

In use, the bottom is removed and loose powder placed therein, on top of the member 8, whereupon the bottom is applied to 55 the ring and the assembled device then placed in position in the vanity case.

When a supply of powder is desired a light tapping by use of a finger of the operator on the expeller member 8, will effect initial depression thereof and consequent 60 vibratory movement due to the spring properties of the member 8, so as to permit some of the powder to enter the central opening 2 of the top, where it may be transferred to a powder pad or puff, or otherwise used, as 65 desired.

In order to accentuate the vibratory movement of the expeller, a coil spring 11, as depicted in Fig. 3 of the drawings may be employed. The bead of the bottom in 70 each instance forms a fulcrum about which the expeller vibrates.

The device obviously may be formed in other than circular shape, without departing from the spirit and scope of the invention.

Having thus described my invention, what I claim as new and desire to secure by Letters Patent is:—

1. A powder dispenser for vanity cases 80 and the like, including a body composed of a ring having an offset forming a seat, a closure for the bottom of the ring having a bottom and a rim which latter engages about the ring, said bottom having a circular upstanding bead, a powder expeller composed of a spring plate of concavo-convex form having its concave side engaged with the bead, and a dished top 85 engaged upon said seat and having an upstanding flange engaged within the ring and arranged on the convex face of the expeller and having a central opening normally closed by the central part of the convex face of the expeller.

2. A powder dispenser, including a body having an open top and having a removable bottom, a raised bead on the bottom, a dished spring expeller plate engaged on its concave side with the bead, and a dished top in 90 said open top of the body having a central opening and having the convex side thereof engaged with the convexed central part of the spring expeller.

3. A powder dispenser, including a body having an open top and having a removable bottom, a raised bead on the bottom, a dished spring expeller plate engaged on its concave side with the bead, and a top in 105 said open top of the body having a central opening normally closed by the central part of the convex side of the expeller.

4. A powder dispenser, including a powder container having a perforated top, a flexible expeller plate for normally closing the perforation of the top and a fixed projection in the container for slidably supporting the plate adjacent to and throughout its periphery upon flexure thereof.
5. In a powder dispenser, a body, an inwardly dished top carried by the body and having an opening, a concavo-convex spring expeller plate beneath said top, having its convex side normally closing said opening of the top, and means to mount the plate to enable same to have vibratory movements, said top and plate having their convex sides confronting each other whereby upon downward flexure of the plate the powder will be moved by the latter upwardly against the convex side of the top and deflected by the latter toward the opening of the top.
6. In a powder dispenser, a body, an inwardly dished top carried by the body and having an opening, a concavo-convex spring expeller plate beneath said top, having its convex side normally closing said opening of the top, and upwardly extending means engaging the concave side of the plate at a plurality of points disposed throughout and adjacent its peripheral portion to support the plate for vibratory movements, said top and plate having their convex sides confronting each other whereby upon downward flexure of the plate the powder will be moved by the latter upwardly against the convex side of the top and deflected by the latter toward the opening of the top.
7. In a powder dispenser, a body, an inwardly dished top carried by the body and having an opening, a concavo-convex spring expeller plate beneath said top, having its convex side normally closing said opening of the top, and a circular upwardly extending bead in the body, engaging the peripheral part of the concave side of the plate to support the latter for vibratory movements.
8. In testimony whereof I have signed my name to this specification.

HARRY BLISS CLEGG.
